(57) **CLAIM**

The ornamental design for a baked dough product, as shown and described.

DESCRIPTION

FIG. 1 is a perspective view of a baked dough product showing our new design.

FIG. 2 is a top plan view of the baked dough product of FIG. 1.

FIG. 3 is a left side elevation view of the baked dough product of FIG. 1, the right side being a mirror image thereof.

FIG. 4 is a rear elevation view of the baked dough product of FIG. 1.

FIG. 5 is a front elevation view of the baked dough product of FIG. 1; and,

FIG. 6 is a bottom plan view of the baked dough product of FIG. 1.
